UNITED STATES PATENT OFFICE.

EDMOND COIGNET, OF PARIS, FRANCE.

ARMORED CONCRETE CONSTRUCTION.

No. 905,056.

Specification of Letters Patent.

Patented Nov. 24, 1908.

Application filed January 22, 1907. Serial No. 353,483.

To all whom it may concern:

Be it known that I, EDMOND COIGNET, a citizen of the French Republic, and residing at Paris, Seine, 20 Rue de Londres, in the Republic of France, have invented certain new and useful Improvements in Armored Concrete Constructions, of which the following is a full, clear, and exact description and for which I have applied for Letters Patent in France, dated January 8, 1906.

The present invention relates particularly to reinforced concrete construction and the object of the invention is to provide an improved reinforcing structure for the beam, substantially as hereinafter specified.

Upon the accompanying drawings which illustrate my invention:—Figure 1 is a perspective view. Fig. 2 is a cross section of the armoring. Fig. 3 is a diagram of one set or system of members viewed longitudinally. Fig. 4 is a similar view of another set of members. Fig. 5 is a plan diagram showing certain parts superposed. Fig. 6 is a longitudinal view of the framework or armoring set up in position. Figs. 7, 8 and 9 are views of certain forms of stirrups employed. Fig. 10 is a perspective view of a double form of the arrangement illustrated in Fig. 1. Figs. 11, 12 and 13 are respectively an elevation and cross-sections on lines 12—12 and 13—13 of Fig. 11, of another form of the invention. Fig. 14 is a plan of Fig. 11. Figs. 15 and 16 are a side elevation and end view of a further modification. Figs. 17 and 18 are a sectional elevation and plan view respectively of another form, and Figs. 19 and 20 show both in sectional elevation forms of hollow slab-provided floors.

The tensional system or members.—The resistance to tension of the concrete being negligible, the armoring alone is to be considered. The new system which I claim and as shown on the drawings at Fig. 1, in perspective, is designed to form a metallic girder of a sufficient rigidity to be able to be placed wholly erected or partly erected in the shuttering where the concrete is poured or deposited, and to resist without displacement of any of its parts the most energetic ramming of the concrete.

The metallic girder is composed essentially of two straight parallel rods or bars of the whole length of the beam to be constructed in armored concrete, the one *e* situated at the lower part of the shuttering the other *f* situated at the upper part of this

latter. These two bars *e* and *f* of any suitable shape, but generally bars of round shape are united by any number of other bars or rods *g* *h* of the same section and shape or of different section and shape. These rods *g* and *h* are cranked at their two extremities, first in the vertical plane for the whole height of the beam, preferably at 45° or 90° or at any other angle, and a second time at 90° in a horizontal plane and for a sufficient length to project outside the beam, so as to bear upon the rod *f* alternately to right and left, and to be attached in any suitable manner to the special armorings of this concrete; some of these rods, the rods *h'* *h''* *h'''* etc. fall to the right and the others the rods *g'* *g''* *g'''* fall to the left of *e*.

In Figs. 2, 3, 4 and 5 I have intended to show that:—

(1) The longitudinal armoring composed of the straight portions of the rods *e* *h* and *g* of lengths and positions determined theoretically by the variation of the bending moments along the beam by reason of the distribution of the load, presents in its whole a section varying according to the value of the moment of the external forces at the point considered.

(2) The parts inclined upwards at 45° or at 90° or in any other manner form transverse armorings converging from the middle towards the extremities in conformity with the requirements of the shearing force relative to beams subjected to a uniformly distributed load which is the most general case. It should be noted that in Fig. 5 the arrangement is quite imaginary since the rods *e* *h* and *g* are superposed.

This framework set up in position is shown in Fig. 6. It will be remarked that all these rods are attached together (see also Fig. 1) by (1) the ligatures *i* (Fig. 6); (2) the four-branched stirrups *k* (Fig. 7), applicable to an armoring completely mounted beforehand, or the four-branched stirrups *k'* (Fig. 8) which can be slipped upon an armoring partly mounted beforehand and (3) the two-branched stirrups *m* (Fig. 9). Thus my new armored or reinforced beam constitutes a rigid whole designed so as to be of equal resistance throughout, both as regards shearing forces and bending moments. Besides, the transverse armorings make only one with the longitudinal tensional armorings and the horizontally cranked extremities being attached to the armorings of the

concrete, form a perfect bond between the members in tension and those in compression; this cranked extremity has also for effect to reinforce the concrete in a strained part, where the armoring is embedded.

It is to be well understood that a beam may comprise one or more of these sets of armoring rods placed side by side, and that from the foregoing it results that the armoring can be constructed in the works itself and of any suitable materials.

System or members in compression.—Nothing prevents the combination of two armorings of the kind previously described so as to form a double armoring completely or partly symmetrical and this combination foreseen for the case of beams without concrete or alternatively acted upon on one side or the other forms an integral part of my invention. The combination of these two armorings of equal resistance can be effected by simple juxtaposition of one armoring represented by Figs. 1 and 2 and an armoring identical, (or if necessary weaker) but inverted or that shown in perspective by Fig. 10. But most often the concrete can more economically resist compression and in this case I maintain constant the rectangular section *a* of the beam A (see Fig. 12) in only the parts where it is sufficient to balance the force of compression and I afterwards enlarge it progressively according to the increase in force, as shown in Figs. 11, 12, 13 and 14. I may also increase progressively the thickness of the flange of the beam or again increase both the thickness and the width, as shown in Figs. 15 and 16. The beam thus constructed being complete as regards compression and elongation, it may be constructed in advance, placed in position and the flooring or covering be finished by means of slabs inlaid as shown in Fig. 20 in transverse section. I may also utilize the maximum space available between two consecutive beams A and A' (see Figs. 17 and 18) and afterwards diminish progressively this width until it is reduced to the thickness of the web *a* of the beam. In practice I leave one or more rectangular openings 1, 2, 3, 4, and 5, 6, 7, 8 (see the right of Fig. 18 in plan and Fig. 17 in longitudinal section) which may be roofed or covered by slabs C of armored concrete (Figs. 19 and 20) of slight thickness, made in advance, or by pavement lights or in any other manner, which is immaterial as regards the resistance of the beam, since up to the line of these hollowed places, the force of compression is considerably reduced. This last arrangement enables me to construct economically hollow monolithic floors. For this purpose once the ceiling B is constructed in armored concrete, I effect the centering of the upper concrete upon the lower concrete and afterwards easily withdraw this centering through

the openings 1, 2, 3, 4, and 5, 6, 7, 8, which have then only to be closed by one of the processes mentioned above (Fig. 19). I am thus able to construct a hollow floor by employing the principle of the procedure represented in Fig. 20 which is a transverse section. For this purpose, the beams D and the ceiling B in armored concrete being constructed in place, the upper flooring is completed by placing thereon slabs of armored cement of small thickness or of pavement lights or in any other suitable manner. These slabs C bear upon the upper part *d* of the armored concrete beams and upon the flange of the concrete executed in place. These slabs may afterwards be incased or fitted in the walls or not.

Having thus described my invention what I claim as such and desire to secure by Letters Patent, is:

85

1. Reinforcing construction for concrete, comprising a compression member and a primary tension member arranged in approximately the same vertical plane, in combination with secondary tension members comprising superposed rods of unequal length arranged on each side of said plane and angled to extend between said compression and primary tension members and oppositely elbowed at their ends across the same, each independently of the other and, spaced apart, substantially as described.

2. Reinforcing construction for concrete, comprising a compression member and a primary tension member, in combination with secondary tension members arranged on each side of said primary tension member, said secondary members comprising superposed rods of unequal length angled to extend to the compression member and oppositely elbowed across the same at their ends, each independently of the other and spaced apart, substantially as described.

3. Reinforcing construction for concrete, comprising a compression member and a primary tension member arranged in approximately the same vertical plane, in combination with secondary tension members comprising superposed rods of unequal length arranged on each side of said plane and angled to extend between said compression and primary tension members and oppositely elbowed at their ends across the same, each independently of the other, together with tie bands uniting all said members, substantially as described.

4. Reinforcing construction for concrete, comprising a primary tension member and a superposed substantially parallel compression member, in combination with secondary tension members arranged on opposite sides of said primary tension member and consisting of superposed rods of unequal length angled to extend between said compression and primary tension members and oppo-

130

sitely elbowed across said tension member, each independently of the other and spaced apart, substantially as described.

5. A concrete beam reinforced by metallic compression and tension members arranged substantially parallel to each other, in combination with secondary superposed tension members of unequal length arranged on each side of the plane of said compression and 10 tension members, angled to extend between the same and elbowed at their ends across the compression member and extending laterally beyond the same to form supports for lateral flanges on the beam, substantially as 15 described.

6. A concrete beam having lateral flanges of varying thickness and reinforced by metallic compression and tension members arranged substantially parallel to each other, in combination with secondary superposed tension members of unequal length arranged on each 20 side of the plane of said compression and tension members, angled to extend between the same and elbowed at their ends across 25 and beyond the same to form supports for lateral flanges on the beam, substantially as described.

7. A beam adapted for use in reinforced concrete construction, comprising primary

tension and compression members, longitudinal reinforcing members of unequal length arranged in sets on opposite sides of said primary tension and compression members and vertically superposed one upon another, said reinforcing members being each independently bent to extend between said tension and compression members and terminally spaced apart and cranked across the same so as to reinforce the beam at all points, substantially as described.

8. A beam adapted for use in reinforced concrete construction, having a main tension member, auxiliary tension members arranged in sets upon opposite sides of the main tension member, and superimposed one 45 upon another, the ends of the auxiliary tension members being angled across an upper chord and the members of one set being shorter than the members of the opposite set and reversely angled.

In testimony whereof I have signed my name to this specification, in the presence of two subscribing witnesses.
